WALL PANEL

Odin L. Scherer, Newfane, N. Y., assignor of one-half to Cornelis De Lange, Lockport, N. Y.

Application January 5, 1940, Serial No. 312,586

1 Claim. (Cl. 20—92)

My invention relates to improvements in wall panels for use more particularly in interior wall and ceiling treatment.

Among the objects of my invention are to provide an interior decorative wall panel combining the advantages of ply, or laminated, construction such as obviating warping, rendering a wall sound-proof, maximum insulation against heat and cold, rigidity and strength, and in which plies are arranged to provide for both flush interlocking edge joints between contiguous panels and hidden nailing to a base structure.

Another object is to provide a wall panel having the advantages above set forth and which is inexpensive to manufacture and easy to secure in place.

Other and subordinate objects are also comprehended by my invention, all of which, together with the precise nature of my improvements, will be readily understood, when the following description and claim are read with reference to the drawing accompanying and forming part of this specification.

In said drawing:

Figure 1 is a view in perspective of the panel showing the front of the same, 25

Figure 2 is a similar view showing the rear of the panel,

Figure 3 is a view in edge elevation, and

Figure 4 is a view in top edge plan showing 30 two of the same panels joined.

Referring to the drawing by numerals, the panel 1 is of rectangular elongated form and 4-ply construction, the plies 14, 15, 16, 17 being secured together permanently by any suitable means such as cement. The plies 14, 15, 16, 17 are all of the same size and rectangular shape and are opposed with edges parallel, the rear plies 15, 16, 17 being diagonally offset, or staggered, relative to the front ply 14 toward one corner of the latter with the second and fourth plies 15 and 17 offset in greater degree than the third ply 16 and aligned relatively to each other. This relation of said plies provides for the plies 15, 17 forming right angled single ply tongues 5 and a groove 6 extending along one side and end of the panel 1, and for the front and third plies forming a groove 7 extending along the

other side and end of said panel. There is thus provided a three-ply margin extending along one side and end of the panel 1, for nailing through, as indicated at 18, to a base wall structure and 5 nailing flat against said structure. As will be clear, the described arrangement also provides for overlapping of the nails of one panel by the front ply 14 of adjoining panels. As illustrated in Figure 4, the ends of such panels 1 are adapted 10 to be interlocked flush in the tongue and groove joints, likewise the sides, as will be clear.

The plies are preferably formed of various types of material, such as wallboard, plasterboard, wood, or boxboard, and may be formed 15 with all plies of the same material to utilize the combined advantages of plies of any one material when secured together, or, each ply may be of different material so as to utilize the different advantages of each material in combination.

In the preferred form of the invention the plies are all of the same thickness or gauge.

The foregoing will, it is believed, suffice to impart a clear understanding of my invention without further explanation.

Manifestly the invention, as described, is susceptible of modification without departing from the inventive concept, and right is herein reserved to such modification as fall within the scope of the subjoined claim.

What I claim is:

A wall panel of the class described comprising a plurality of rectangular-shaped members having their side faces connected together to provide 35 a laminated structure, all the members being of the same width and length, said panel being composed of four members with two of the members in alignment with respect to each other and the other two members being out of alignment relative to the aligned members and also out of alignment with respect to each other to provide tongues and grooves at the edges of the panel adapted to mate with tongues and grooves in adjacent panels, said tongues and 40 grooves extending around all four sides of the panel, the corresponding edges of all of said members being substantially in parallel relation.

ODIN L. SCHERER.
